CLAIM

The ornamental design for an automobile, as shown and described.

DESCRIPTION

FIG. 1 is a perspective view of an automobile according to the present invention.

FIG. 2 is a front view of the automobile of FIG. 1.

FIG. 3 is a rear view of the automobile of FIG. 1.

FIG. 4 is a left side view of the automobile of FIG. 1.

FIG. 5 is a right side view of the automobile of FIG. 1; and, FIG. 6 is a top view of the automobile of FIG. 1.

A bottom view thereof is omitted since it does not contain ornamental features.

1 Claim, 6 Drawing Sheets

FIG. 1

FIG. 2

FIG. 3

FIG. 4

FIG. 5

FIG. 6
